UNITED STATES PATENT OFFICE

HIRAM PERCY MAXIM AND ROLAND B. BOURNE, OF HARTFORD, CONNECTICUT, ASSIGNEES, BY MESNE ASSIGNMENTS, TO THE MAXIM SILENCER COMPANY, OF HARTFORD, CONNECTICUT, A CORPORATION OF CONNECTICUT

SILENCER

Application filed June 27, 1927. Serial No. 201,951.

This invention appertains to a wave damping device for the silencing of noise, or for the attenuating, attriting, and impeding of certain waves or pulsations in a gaseous medium which may not be ordinarily classified as sound but which partake of the same nature thereof.

This invention aims at the accomplishment of its purpose by assembling a plurality of identical spirally wound sheets in superposed interwound relation between two separate header portions, said sheets forming a grouping outwardly confined by a substantially cylindrical form and inwardly surrounding a substantially cylindrical central space or chamber so that the gases may pass through an opening in one of the headers into the central chamber and from there through the various narrow passages formed between adjacent spirally wound sheets to the exterior. In some cases, one or more additional groupings of similarly shaped and interwound sheets is arranged between headers common to all groupings, consecutive groupings concentrically enclosing the next inner grouping with an annular chamber between. Further combinations of several such concentric groupings within a common shell are possible.

The object of the invention is to improve and simplify the construction of such silencers, whereby the cost of manufacture may be lessened and the assembly of parts greatly facilitated. In this connection, a feature of importance resides in the means for spacing the spirally wound sheets one from the other and for spacing concentrically disposed groupings one from the other, as will hereinafter appear.

Referring to the drawings which show a preferred embodiment of the invention:—

Fig. 1 is a side elevation of a sheet grouping apart from the headers;

Fig. 2 is an end view of the same showing a second and smaller grouping in nested relation therewith; and

Fig. 3 is a longitudinal section taken through line 3—3 of Fig. 2 of the two concentric sheet groupings mounted between headers to form a complete silencing apparatus.

Referring more particularly to the draw-

ings, the sheet groupings (separately shown in Figs. 1 and 2) are made up of a plurality of superposed spirally wound sheets 1 which are spaced apart as shown to provide a plurality of passages 2 arranged in parallel and leading from the interior chamber to the exterior. The several sheets 1 are preferably arranged with the ends in overlapping relation, the inner straight edges 4 of said sheets being preferably spaced apart at equal distances and the outer edges 5 of said sheets likewise being spaced apart at equal distances. In this way, equi-spaced inlets for the several passages 2 are provided at the interior of said chamber and equi-spaced outlets for said passages are provided exteriorly.

The sheets 1 are preferably spaced apart a very small distance—approximately one-fiftieth of an inch—so as to provide a passage 2 of an extremely narrow or small depth relative to the length of said passage. In our preferred form of silencing unit, the relation between the depth of each passage to its length is approximately in the proportion of one to two hundred. These passages are much narrower in depth than passages heretofore employed in silencer construction and we have found that the dissipation of wave energy is greatly increased in such small passages, probably due to the far greater scrubbing action and attrition to which said waves are subjected than in larger passages. Such narrow passages are particularly effective in the suppression of waves of high frequency. These passages 2 may be as small as is practical to make and space them and yet provide a free flow of gas therethrough. In order to take care of any desired volume of gas with such a silencing unit, the narrow passages described may be multiplied in number to any reasonable extent. The number of passages possible in such an arrangement as shown will obviously be a function of the inner circle on which the inner ends of the spirally wound edges of the sheets are set since inlets of said

passages must divide up said circle. The multiplication of said passages involves the placing in superposed interwound relation of a great many spirally wound sheets. The assembly in properly spaced relation of a great

number of such sheets in the manner described offers considerable difficulty unless suitable spacing means are provided for separating the sheets.

- 5 The means for spacing apart the sheets for each silencing unit preferably consist of an integral offset projection or bead which may be rolled into the sheet lengthwise thereof for suitable contact with the next adjacent sheet.
- 10 As shown in Fig. 1, a plurality of such beads 6 are formed on each sheet and are spaced apart transversely thereof and extend lengthwise thereof in parallel relation to the spirally wound edges of the sheets. Obviously, the beads of each sheet should be relatively disposed so that the projecting side of one will not enter into the depressed side of another. For this purpose, the beads of one sheet are preferably displaced in staggered relation 15 with the beads of the next adjacent sheet, as clearly appears in Fig. 3. The beads being distributed over the entire surface of the sheets will also serve to subdivide the spirally wound passages into a number of channels 20 of smaller width whereby the scrubbing action is further augmented due to an increased friction surface for the gases passing on both sides of a bead.

When it is desirable to combine two or more 30 sheet groupings, they may be made of different diameters and arranged in nested relation one within the other, as shown in Fig. 2. In this way concentric double, treble or multiple groupings can be formed. Means 35 should be provided for spacing said concentric groupings and in our preferred embodiment this consists of turning up integral corner portions 7 at the outer ends 5 of the sheets making up the inside grouping, which turned 40 up portions will contact with the inner portions of the sheets 1 in the outside grouping. In forming a complete silencing apparatus, two such concentric groupings may be mounted between a header member 8 having an 45 inlet 9 and a header member 10; the entire assembly being held together by suitable tie bolts 11, as shown in Fig. 3. It will be observed by this construction that an interior chamber 12 within the inside groupings 50 is provided and likewise an annular space or secondary chamber 13 is provided between the two groupings, as shown.

In operation, it will be understood that 55 gases and sound waves entering the interior chamber of a sheet-grouping will be distributed through the various inlets of said inside chamber and flow through the spiral passages to the exterior, the sound waves being subdivided, scrubbed and attenuated during the 60 process so as to emerge with very little energy.

This process is repeated through such 65 further groupings as are employed and it is to be understood that various combinations and arrangements, other than as shown, of such groupings in cascade may be employed

to meet the exigencies of each situation in connection with the handling of sound silencing problems.

What we claim is:

1. A silencer comprising two headers one 70 of them with an opening therethrough, a grouping of substantially identical, spirally wound sheets, whose spirally wound edges abut said two headers, said sheets arranged in superposed interwound relation so that in 75 a cross-section parallel to the headers the inner and the outer ends of the wound edges are substantially symmetrically spaced on an inner and an outer concentric circle respectively, the inner straight edges of the sheets 80 together with the header walls defining an inner centrally extending chamber communicating with the exterior through said opening, and a plurality of integrally formed projections on said spirally wound sheets, said 85 projections being parallel to the header engaging edges of the sheets and being axially displaced with respect to each other on two adjacent sheets, thus defining the depth and width of the spirally winding passages 90 formed between two adjacent sheets.

2. A silencer comprising two headers one 95 of them with an opening therethrough, a grouping of substantially identical, spirally wound sheets, whose spirally wound edges abut said two headers, said sheets arranged in superposed interwound relation so that in 100 a cross-section parallel to the headers the inner and the outer ends of the wound edges are substantially symmetrically spaced on an inner and an outer concentric circle respectively, the inner straight edges of the sheets together with the header walls defining an inner centrally extending chamber communicating with the exterior through said opening, and a plurality of integrally formed projections on said spirally wound sheets, said 105 projections being about equidistantly distributed over the whole surface of the sheets parallel to the header engaging edges of the 110 sheets and axially displaced with respect to each other on two adjacent sheets, thus defining the depth and width of the spirally winding passages formed between two adjacent 115 sheets.

3. A silencer comprising two headers one 120 of them with an opening therethrough, a grouping of substantially identical, spirally wound sheets, whose spirally wound edges abut said two headers, said sheets arranged in 125 superposed interwound relation so that in a cross-section parallel to the headers the inner and the outer ends of the spirally wound edges are substantially symmetrically spaced on an inner and an outer concentric circle respectively, the inner straight edges of the sheets together with the header walls defining an inner centrally extending chamber 130 communicating with the exterior through said opening, a plurality of integrally formed

projections on said spirally wound sheets,
said projections being parallel to the header
engaging edges of the sheets and being ax-
ially displaced with respect to each other on
5 two adjacent sheets, thus defining the depth
and width of the spirally winding passages
formed between two adjacent sheets in the
grouping, one or more additional groupings
10 of similarly formed spirally wound sheets
arranged between said same headers concen-
trically about the first grouping on circles of
large enough diameter to leave annular cham-
bers between two successive groupings, the
uniform width of these annular chambers
15 being secured by bent corner portions of ad-
jacent spiral sheets.

In testimony whereof we have affixed our
signatures.
